Design #353

Dec. 353

Gardner Chilson of Boston, Mass.
Letters Patent No. 353 - dated March 4, 1851.

The Schedule referred to in these Letters Patent and making part of the same.

To all persons to whom these Presents shall come:

Be it known,

that I, Gardner Chilson of Boston, in the County of Suffolk and State of Massachusetts, have invented, or produced, a new and original design for a register, for furnaces &c. and I do hereby declare that the following description and accompanying drawing form a full and exact specification and representation of the same.

The register is of a rectangular form, as shown in the drawing, which is a plan or top view of the same. Within this rectangle is a smaller one, formed by the bars a, a, a, a. This inner rectangle is connected to the outer edge or surface b, b, b, b, of the register, by the curved bars c, c, &c. running in different directions from the corners towards the centres of each side, forming the latticed work or apertures, d, d, &c. of the shape shown in the drawing. In each corner of this inner rectangle, a small square is formed by the bars e, e, at right angles to the bars a, a, &c. The adjacent bars a, a, and e, e, are connected to each other, by the curved bars f, f, f, &c. which terminate in the short, straight bars g, g, &c. which are attached to the centre bars, forming the several spaces h, h, &c. and the space i, in the centre of the squares. The space between each of these squares is occupied by the rectangles formed by the straight bars a, a, e, e, h, h, &c. From each of the sides a, a, h, h, proceed the semicircular bars l, l, &c. forming semicircular spaces m, m, &c. and straight bars m, m, running across each other, and forming the diamond shaped apertures o, o, &c. and the irregular shaped apertures p, p, &c. between the said semicircular and straight bars.

The bars k, k, k, k, form the remaining rectangle in the centre of the register. In the centre of the register is the ring q, q, enclosing the four leaved star r, r, formed by the curved or notched bars s, s, &c. leaving

the circular space τ in the centre, the arched spaces u, u, f, c in the centre of each leaf, and the curved spaces v, v , between the ring g, g , and the leaves. Draw the outer edge of this ring, the curved bars or branches $w, w, \& c.$ run to the bars h, h, k, k , forming the irregular, curved apertures $y, y, \& c.$

Having thus described my new design, I shall state my claim as follows:

What I claim as my invention or production, & desire to have secured to me by Letters Patent, is the new design, hereinabove described, for a register for furnaces &c. of rectangular form having within it a smaller rectangle connected to the edge of the register, by curved bars, of the shape shown in the drawing, said inner rectangle having a square in each corner, and small rectangles within its sides, said squares being ornamented with curved bars, forming the lattice work $h, h, i, i, \& c.$ and said smaller rectangles being ornamented with semicircular and diamond shaped lattice work; and a rectangle in the centre of the register, ornamented with irregular curved branches or bars, proceeding from its sides, to a ring enclosing a four notched leaved star, the whole forming a lattice or open work, for the heat to pass through, all as herein above described.
